ACTUATING MECHANISM FOR ACCOUNTING-REGISTERS.

1,084,633.

Specification of Letters Patent. Patented Jan. 20, 1914.

Application filed March 27, 1909. Serial No. 486,115.

To all whom it may concern:

Be it known that I, FREDERICK O. HEUSER, a citizen of the United States, residing at Chicago, in the county of Cook and State of Illinois, have invented a certain new and useful Improvement in Actuating Mechanism for Accounting-Registers, of which the following is a full, clear, concise, and exact description, reference being had to the accompanying drawings, forming a part of this specification.

My invention relates to an actuating mechanism for accounting registers, and has particular reference to a polyphase electromagnetic actuating mechanism.

Hitherto, in actuating registers of a mechanical accounting system, it has been necessary to provide a separate actuating mechanism for each register, notably, in the case of a time register and a wage register, adapted to indicate respectively, the time and wages of any individual workman. According to the system described in the application of Lynn A. Williams, Serial No. 474323, a single register is provided having time and wage indicators, these indicators being geared together in a ratio proportional to the time units and the wage units of any workman. In Williams' system, however, when the rate of any workman is changed, it is necessary to either change the gearing of the register or replace it by one which is suitably geared.

By my improved system, it is possible to actuate two registers at differing rates by means of a single mechanism. This mechanism consists of a plurality of electromagnets, one terminal of each electromagnet being suitably connected to a rotary disk. Part of the periphery of this disk is of insulating material. The actual connection to this disk is made by means of brushes and the disk is electrically connected with a source of current. Each of the second terminals of the electromagnets is suitably connected to a brush which bears on the surface of a second rotary disk, the periphery of which alternates with electrically conducting and insulating segments. The second disk may be made to rotate at the same or a different rate of speed from that of the disk first mentioned, and it is electrically connected to the other pole of the above mentioned source of current. The brushes are so disposed on this second disk that one

brush is constantly in contact with a conducting section of the periphery, whereas the other brushes are meanwhile resting on an insulated portion of the periphery. It is now evident that as the two disks are rotated, one set of terminals of the electromagnets will simultaneously be in connection with one pole of a battery, which acts as a source of current, while the second terminals of the electromagnets are successively brought into electrical connection with the second pole of the battery, in such manner that the electromagnets are successively energized, one of these electromagnets always being energized, while the first set of terminals remains in connection with one pole of the battery. It is now evident that by rotating the first disk at a constant rate of speed, an armature adapted to be attracted when any one of the electromagnets is energized would be moved at a rate corresponding to the rate at which the said disk is rotated. On the other hand, when the second disk is rotated, the electromagnets are successively energized and if an armature is associated with each electromagnet, and these armatures are mechanically connected together by a shaft, this shaft will be actuated at a rate which corresponds to the sum of all of the energizations of the individual electromagnets, and is entirely independent of the rate at which the first armature is moved. I accomplish this result in my invention as will be described in detail hereafter.

The movements of the first armature which becomes actuated only on the energization or deenergization of the group of electromagnets, are made to actuate a time register, whereas the rotation of the shaft which is at a rate corresponding to the sum of the energizations of the various individual electromagnets, is made to actuate a wage register.

Not only may my invention be applied to accounting systems, but it is of great practical utility in other fields; as for example, in the operation of electric motors where an armature would be employed, which would be adapted to be retained in a suitable position, as long as any one of the electromagnets of a motor were energized, and would assume its normal position only when the current is cut off from all of the electromagnets. In this way, by attaching a suitable register to the armature, it would readily

be possible to thus indicate the number of times that a motor has been started or stopped.

Taking up the description of my invention in detail, in the drawings, Figure 1 is a plan of a three phase actuating mechanism for a time and wage register, Fig. 2 is a side elevation of Fig. 1 and Fig. 3 is a diagrammatic representation showing the connections of a three-phase actuating mechanism with a source of current, and the method of breaking the connections with said source of current.

In Fig. 1, 1, 2 and 3 are electromagnets insulated from one another, but connected on the ends by the insulating frames 4 and 5. Each of these electromagnets is supplied with suitable windings and connected with a source of current as shown in Fig. 3, these connections, for the sake of simplicity, being omitted in Figs. 1 and 2. The electromagnets 1, 2 and 3 are provided with cores, one set of poles being shown at 6, 7 and 8, and the other set of poles at 9, 10 and 11. The electromagnets are mounted in a suitable frame 12, of non-magnetic material, preferably brass. As best shown in Fig. 2, the poles 6, 7 and 8 are each provided with an extension 13, which passes under the electromagnet and terminates in a pole-piece 14. In order to add rigidity to the mechanism, the pole pieces 6, 7 and 8 are connected by means of a non-magnetic rod 15, preferably of brass. On the ends of the rod 15 are provided frames 16, and 17, which are joined by a bar of magnetic material 18. The bar 18 is adapted to act as an armature and on energization of any one of the electromagnets, when the poles 6, 7 or 8 are magnetized the armature 18 is attracted. A spring 19 is adapted to retain the armature 18 and the frames 16 and 17 in their normal positions, as shown in Figs. 1 and 2. As most clearly indicated in Fig. 2, there is an air gap between the common armature 18 and the poles 6, 7 and 8 when the armature is in its normal position. Upon the energization of any one of the electromagnets the magnetic flux tends to shorten this air gap as much as possible, as well understood by those skilled in the art. Hence the iron armature is attracted against the action of the spring 19. On the inner side of the frame 16 is pivoted a pawl 20, which is adapted to coöperate with a ratchet wheel 21, rigidly mounted on the shaft 22. The pawl 20 is held in its engaging position by a spring 23. It now becomes evident that when the armature 18 is attracted to the pole 8, the ratchet wheel 21 is caused to revolve. The shaft 22 is connected with a time register 24, which is held in position on the frame 12 by means of the screws 25 and 26. The indicator of this register may be seen through an opening

27, which is cut in the frame 12. The amount of rotation of the shaft 22 is therefore indicated in the register 24 and as will be described in detail hereinafter, this indication corresponds to the time during which the actuating mechanism is in operation.

Associated with the poles 9, 10 and 11 are the armatures 28, 29 and 30, which are mounted on a shaft 31, which is suitably supported by the brackets 32. Each of these armatures consists of four arms most clearly shown in Fig. 2, these arms being at right angles to one another. The armatures 28, 29 and 30 are mounted on the shaft 31, so that the arms of the armatures will lie in separate planes. In Fig. 2 the arms of the armature 30 are shown at 33. The arms of the armature 29 are shown at 34 and of the armature 28 at 35.

As described above, each of the pole-pieces 6, 7 and 8 is provided with an extension which is best shown in Fig. 2 at 13, this extension terminating in a pole-piece 14. It is now clear that when the electromagnet 3 is energized, the pole pieces 11 and 14 will become effective and attract the nearest arms 33 of the armature 30 to the position indicated in Fig. 2. When the electromagnet 3 is deenergized and the electromagnet 2 is energized, the nearest arms 34 of the armature 29 will be similarly attracted to the pole 10 and the corresponding pole which lies in a position corresponding to the pole 14 of Fig. 2. The arms 35 will thus be made to occupy the position in which the arms 34 are shown in Fig. 2, and the arms 33 will occupy the positions shown by 35 in Fig. 2. When the electromagnet 2 is deenergized, and the electromagnet 1 is energized, the arms 35 will be attracted to the pole 9 and the pole corresponding to the pole 14 of Fig. 2, and the arms 33 will occupy positions of the arms 33 of Fig. 2. When electromagnet 1 is deenergized, and electromagnet 3 is energized, the position shown in Fig. 2 will be again assumed. It is now clear that by the successive energizations of the three electromagnets 1, 2 and 3, the shaft 31 is caused to revolve. Rigidly attached to the shaft 31 is gear 36 which is in mesh with the gear 37 rigidly mounted on shaft 38. Shaft 38 is directly connected with a wage register 39 which is suitably attached to the frame 12 by the screws 40 and 41. The indicator of this register is visible through an opening 42 cut in the frame 12. It is evident that the register will be actuated on each energization of any one of the electromagnets 1, 2 or 3, and as will be described hereinafter, the number of these energizations may be made to correspond to a rate of wages.

Taking up now the operation of my system as a whole, as shown in Fig. 3. On the time controlled shaft 43 are rigidly mount-

ed disks 44, 45 and 46 of electrically conductive material. On the peripheries of these disks are segments of insulating material shown respectively at 47, 48 and 49. Bearing on the peripheries of the disks are the brushes 50, 51 and 52, which are connected by the conductors 53, 54 and 55, with the switches 56, 57 and 58. The diagram shown in Fig. 3, represents my system as applied to three workmen, three of the electromagnetic mechanisms represented in Fig. 1 being shown at A, B and C. The conductors 59, 60 and 61 connect the switches 56, 57 and 58 with these actuating mechanisms A, B and C, one set of terminals of the actuating mechanism A being connected to the conductor 59 by the conductors 62, 63 and 64. In a similar manner, the terminals of the actuating mechanism B are connected to the conductor 60, by the conductors 65, 66 and 67, and of the actuating mechanism C by the conductors 68, 69 and 70. Mounted on the shaft 43 is also the disk 71, the periphery of which is provided with alternate segments 72, of insulating material. Between these insulating segments are the conducting segments 73. The shaft 43 is provided with a section of insulating material 74, so that the portion of the shaft 43 on which the disk 71 is mounted, is electrically disconnected with the section of the shaft on which the disks 44, 45 and 46 are mounted. The disk 71 may also be mounted on a separate shaft, the speed of which can be regulated as desired. The section of the shaft 43 on which the disks 44, 45 and 46 are mounted, is electrically connected with one pole of a battery 75, through the conductor 76. The other pole of the battery 75 is connected through the conductor 77 with that portion of the shaft 43, on which the disk 71 is mounted. The brushes 78, 79 and 80 are adapted to bear on the periphery of the disk 71, in such manner that as the disk 45 is rotated, one of the brushes is constantly in contact with a conducting segment 73, while the other two brushes rest on an insulating segment or insulating segments 72. The brushes 78, 79 and 80 are connected to one set of terminals of the electromagnetic device T, by the conductors 81, 82 and 83. The purpose of this electromagnetic device T will be described hereafter. Each of the electromagnets 84, 85 and 86 of the actuating mechanism T has its second terminal connected to the conductors 87, 88 and 89, respectively. The conductor 87 is connected with the second terminal of the electromagnet 3 of the actuating mechanism A, and through the conductors 90 and 91 is similarly connected with a terminal of the electromagnet 3 of the actuating mechanisms B and C. Similarly the conductor 89 is connected with one of the terminals of the electromagnet 2, of the actuating mechanisms

A, B and C, and the conductor 89 with one of the terminals of the electromagnet 1 of the actuating mechanisms A, B and C.

The operation of my system will now become clear. Let us consider the case of the actuating mechanism A. While the brush 50 bears on the conducting segment of the disk 44, one terminal of each of the electromagnets 1, 2 and 3 of the actuating mechanism A is brought into electrical connection with one pole of the battery 75. As the disk 71 is rotated, each of the second terminals of the electromagnets 3, 2 and 1 is successively brought into electrical connection with the second pole of the battery, through the conducting segments 73 of the disk 71, which is mounted on shaft 43, and the conductor 71. Inasmuch as the actuating mechanism A which is connected to the conductors 62, 63 and 64 is in electrical connection with one of the poles of the battery 75, while the switch 56 is closed and the brush 50 bears on the conducting segments of the disk 44, each of the electromagnets 3, 2 and 1 will be successively energized when the terminals connected with the conductors 87, 88 and 89 are successively connected with the second pole of the battery 75, as the brushes 78, 79 and 80 are brought into connection with the segments 73 of the disk 71. When the disk 44 is rotated into such position that the brush 50 bears on an insulating segment of the disk 44, of course none of the electromagnets of the actuating mechanism A will be energized, although the terminals connected with the conductors 87, 88 and 89 are being successively brought into electrical contact with one pole of the battery 75. The operation of the actuating mechanisms B and C is exactly similar to that of A. As shown in the diagram, the conducting segments of the disks 44, 45 and 46 are made of three different lengths. By this means the individual electromagnets of the actuating mechanism are energized a greater number of times, as the length of the conducting segment is increased.

The practical application of my device to accounting systems is now apparent. While the brush 50 associated with the actuating mechanism A bears on the conducting segment of the disk 44, the armatures 18 of Fig. 1 will be attracted by the poles 6, 7 or 8, and when the brush on the rotation of the disk 44 reaches an insulating segment, the armature 18 will resume its normal position as shown in Figs. 1 and 2, thereby giving a single actuation to the time register 24. It is thus evident that the length of the conducting segment has absolutely no effect on the actuation of the time register. On the other hand, in the case of the armatures associated with the opposite poles of the electromagnets, the energization of each individual electromagnet produces a movement

- of the armature and thereby the wage register 39 is actuated. It is thus clear that although the time register associated with the actuating mechanism A will be actuated at exactly the same rate as the time register associated with the actuating mechanism C, the wage register associated with A will be actuated at a slower rate than the wage register associated with C, for the reason that the terminals of the mechanism A associated with the conductors 87, 88 and 89 will not make as many successive connections with the battery 75, during the connection of the brush 50 with the conducting segment of the disk 44, as will the terminals of the actuating mechanism C connected with the conductors 87, 88 and 89, during the connection of the brush 52 with the conducting segment of the disk 46.
- 20 The actuating mechanism T is provided for the purpose of totalizing the actuations of the wage registers of the mechanisms A, B and C, and it is clear that when any one of the electromagnets 3, of the actuating mechanisms A, B or C is energized, the electromagnet 84 will be energized at the same time. Similarly 85 and 86 will be energized during the energization of any of the electromagnets 2 and 1, respectively. In this way the total energizations of all nine of the electromagnets of the three actuating mechanisms will be totalized in the actuating mechanism T, to which a total wage register may be attached.
- 35 It is evident that considerable departure may be made from the exact mechanism which I have described, without departing from the spirit of my invention, and what I claim as new and desire to cover by Letters Patent is:
1. In a device of the class described, a plurality of electromagnets, means to successively energize said electromagnets during a given period, a mechanism adapted to be actuated on the successive energization of any of said electromagnets and the de-energization of all of said electromagnets, and a register actuated by said mechanism, said register adapted to indicate the number 45 of times of energization of any, or deenergization of all of said electromagnets.
2. In a device of the class described, a source of electric current, a plurality of electromagnets, an electric conductor, means for successively connecting each of said electromagnets with said conductors, means for connecting said conductor with said source of current, at least one of said electromagnets being energized at any given time during 55 the connection of said conductor with said source, time controlled means for periodically breaking the connection of said conductor with said source, a mechanism adapted to be actuated by said electromagnets on the successive making and breaking of the 60 circuit connecting said conductor with said source, and a register actuated by said mechanism, said register adapted to indicate a lapse of time.
3. In a device of the class described, the combination with a source of electric current, of a plurality of electromagnets, means for connecting a set of terminals comprising one terminal of each electromagnet to said source of current, means for periodically breaking the connection of said first terminals with said source of current, means for successively connecting the second terminals of the electromagnets with said source of current, at least one of said second terminals being so connected at any given time, a mechanism adapted to be actuated by said electromagnet on the successive making or breaking of the connection of said first terminals with said source of current, and a register actuated by said mechanism, said register adapted to indicate a lapse of time.
4. In combination, a source of electric current, a plurality of electromagnets, means for connecting a set of terminals comprising one terminal of each electromagnet to said source of current, means for periodically breaking the connection of said first terminals with said source of current, means for successively and periodically connecting the second terminals of each of said electromagnets to said source of current, at least one of said second terminals being so connected at any given time, a mechanism adapted to be actuated by said electromagnets on the successive making or breaking of the connection of said first terminal with said source of current, a register associated with said mechanism and adapted to indicate a lapse of time, a second mechanism associated with said electromagnets and adapted to be actuated on the making or breaking of the connection of any second terminals with said source during the connection of said first terminals with 100 said source, and a register adapted to be actuated by said second mechanism to indicate the accumulation of wages at a predetermined rate.
5. In combination, a source of electric current, a plurality of electromagnets, means for connecting a set of terminals comprising one terminal of each electromagnet to said source of current, means for periodically breaking the connection of said first terminals with said source of current, means for successively connecting the second terminal of each of said electromagnets to said source of current at a rate corresponding to a predetermined rate of wages, at least one of said second terminals being so connected at any given time, a mechanism adapted to be actuated by said electromagnets on the successive making or breaking of the connection of said first terminals with said source of 115 current, and a register adapted to indicate a lapse of time.
6. In combination, a source of electric current, a plurality of electromagnets, means for connecting a set of terminals comprising one terminal of each electromagnet to said source of current, means for periodically breaking the connection of said first terminals with said source of current, means for successively connecting the second terminal of each of said electromagnets to said source of current at a rate corresponding to a predetermined rate of wages, at least one of said second terminals being so connected at any given time, a mechanism adapted to be actuated by said electromagnets on the successive making or breaking of the connection of said first terminals with said source of 120 current, and a register adapted to indicate a lapse of time.
7. In combination, a source of electric current, a plurality of electromagnets, means for connecting a set of terminals comprising one terminal of each electromagnet to said source of current, means for periodically breaking the connection of said first terminals with said source of current, means for successively connecting the second terminal of each of said electromagnets to said source of current at a rate corresponding to a predetermined rate of wages, at least one of said second terminals being so connected at any given time, a mechanism adapted to be actuated by said electromagnets on the successive making or breaking of the connection of said first terminals with said source of 125 current, and a register adapted to indicate a lapse of time.
8. In combination, a source of electric current, a plurality of electromagnets, means for connecting a set of terminals comprising one terminal of each electromagnet to said source of current, means for periodically breaking the connection of said first terminals with said source of current, means for successively connecting the second terminal of each of said electromagnets to said source of current at a rate corresponding to a predetermined rate of wages, at least one of said second terminals being so connected at any given time, a mechanism adapted to be actuated by said electromagnets on the successive making or breaking of the connection of said first terminals with said source of 130 current, and a register adapted to indicate a lapse of time.

- current, a register actuated by said mechanism, said register adapted to indicate a lapse of time, a second mechanism associated with said electromagnets and adapted to be actuated on the making or breaking of the connection of any second terminal with said source during the connection of said first terminals with said source, and a register associated with said second mechanism, said 6 register adapted to indicate the accumulation of wages at said predetermined rate.
6. In combination, a source of electric current, a plurality of electromagnets, means for connecting a set of terminals comprising 15 one terminal of each electromagnet to said source of current, means for periodically breaking the connection of said first terminals with said source of current, means for successively and periodically connecting the 20 second terminals of said electromagnets to said source of current, at least one of said second terminals being so connected at any given time, an armature adapted to be attracted on the energization of any of said 25 electromagnets, means for moving said armature to its normal position when said first terminals are disconnected with said source of current, thereby failing to energize any of said electromagnets, and a register associated 30 with said armature and adapted to be actuated by the successive movements of said armature from its normal to its alternate position.
7. In combination, a source of electric current, a plurality of electromagnets, means for connecting a set of terminals comprising one terminal of each electromagnet to said source of current, means for periodically breaking the connection of said first terminals with said source of current, means for successively and periodically connecting the 35 second terminals of each of said electromagnets to said source of current, at least one of said second terminals being so connected 40 at any given time, an armature adapted to be attracted on the energization of any of said electromagnets, means for moving said armature to its normal position when said first terminals are disconnected with said 45 source of current, thereby failing to energize any of said electromagnets, a register associated with said armature and adapted to be actuated by the successive movements of said armature from its normal to its alternate 50 position, an armature associated with each of said electromagnets and adapted to be attracted by the energization of said electromagnet, a shaft on which said armatures are rigidly mounted, the movement of any armature thereby rotating said shaft and all of said armatures connected to said shaft, and a register connected with said shaft, said register adapted to indicate the total energizations of said electromagnets.
- 55 8. In an accounting system, a time register, a wage register, and a common electromagnetic actuating mechanism associated with said registers, said actuating mechanism adapted to advance said time register at a rate corresponding to the lapse of time 70 and said wage register at a rate corresponding to a predetermined rate of wages.
9. In an accounting system, a time register, a wage register, and a polyphase electromagnetic actuating mechanism associated 75 with said registers, said actuating mechanism on energization adapted to advance, said time register at a rate corresponding to the lapse of time and said wage register at a rate corresponding to a predetermined 80 rate of wages.
10. In an accounting system, a source of electric current, a time register, a wage register, a plurality of electromagnets, a time controlled rotary conductor, means for 85 connecting one set of terminals of said electromagnets to said conductor, said conductor having an insulated portion adapted to break the electrical connection between said terminals and said conductor, means for connecting said conductor with said source of current, a second time-controlled rotary conductor, means for independently connecting each of the second terminals of said electromagnets to said second conductor, said 90 conductor provided with insulated portions, so that said terminals will be successively brought into electrical connection with said conductor, means for actuating said time register at a rate corresponding to the number of times the electrical connection between said first terminals and said first conductor is broken, and means for actuating said wage register at a rate corresponding to the number of times the electrical connection between all of said second terminals and said second conductor is broken during 95 the electrical connection of said first terminals with said first conductor.
11. In an accounting system, a source of electric current, a time register, a wage register, a polyphase electromagnetic mechanism associated with said registers, means for connecting said mechanism with said source of current, means for actuating said time register at a rate corresponding to the rate at which electrical connection between said mechanism and said source is broken, and means for actuating said wage register at a rate corresponding to the rate at which 100 the electrical connections between the individual electromagnets and said source are broken.
12. In an accounting system, a source of electric current, a wage register, a time register, a three-phase electromagnetic actuating mechanism associated with said registers, time controlled means for periodically and successively energizing the electromagnets of said mechanism by said source, at 105 115 120 125 130

- least one of said electromagnets being energized at a time during a given period, time controlled means for breaking the electrical connection of said mechanism with said source, an armature adapted to be attracted to its alternate position when any of said electromagnets is energized, and to assume its normal position when the electrical connection between said mechanism and said source is broken, means for actuating said time register at a rate corresponding to the rate of movement of said armature from its normal to its alternate position, an armature associated with each electromagnet of said mechanism, a shaft on which said armatures are rigidly mounted in a plurality of longitudinal planes, each of said armatures adapted to be attracted by its corresponding electromagnet as such electromagnets are successively energized, thereby rotating said shaft and all of said armatures on said shaft, and means for actuating said wage register at a rate corresponding to the rate of rotation of said shaft.
- 25 13. In combination, a plurality of electromagnets, a separate armature associated with each electromagnet, a common armature adapted to be actuated by any of the electromagnets, means for energizing the individual electromagnets in succession, a register adapted to be operated by said separate armatures, and a second register adapted to be operated by said common armature.
14. In a device of the class described, a plurality of energizing windings, an electromagnetic mechanism individual to each of said windings and adapted to be actuated upon the energization of the associated winding, a common electromagnetic mechanism adapted to be actuated by any or all of said windings when energized, means for closing in succession the circuits of said windings, a register adapted to be operated by said individual electromagnetic mechanisms, and a second register adapted to be operated by said common electromagnetic mechanism.
15. In combination, a plurality of electromagnets, a common armature at one end of said electromagnets adapted to be actuated upon the energization of any or all of the electromagnets, an individual armature at the other end of each electromagnet, each individual armature being adapted to be actuated by the associated electromagnet and by none other, switching mechanism for closing electrical circuits in succession through the individual electromagnets, a register adapted to be operated by said individual armatures, and a second register adapted to be operated by said common armature.
16. In combination, a source of electric current, a plurality of electromagnets,

means for successively energizing the electromagnets and deenergizing each of them after the successive energization has been effected, an armature associated with each electromagnet and adapted to be actuated thereby, a common armature adapted to be actuated by any of the electromagnets, a register adapted to be operated by the individual armatures, and a second register adapted to be operated by the common armature.

17. In combination, a source of electric current, a pair of registers, a polyphase electromagnetic mechanism associated with said registers, means for connecting said mechanism with the source of current, means for actuating one register at a rate corresponding to the rate at which the electrical connection is broken between the source of current and the individual electromagnets, and means for actuating the other register at a rate corresponding to the rate at which the electrical connection is broken between the source of current and the electromagnetic mechanism as a whole.

18. In combination, a pair of registers, and a common actuating device for said registers, said device provided with means for actuating one of said registers, and means for variably and independently actuating the second of said registers.

19. In combination, a pair of registers, and a common actuating device for said registers, said device provided with means for actuating one of said registers at a predetermined rate and means for variably actuating the second of said registers at any one of a plurality of predetermined rates.

20. In combination, a wage register, a time register, and a common actuating device associated with said registers, said device provided with means for actuating said time register, and means for independently actuating said wage register, the proportionate actuations of said register thereby being variable.

21. In combination, a wage register, a time register, and a common actuating device associated with said registers, said device provided with means for actuating said time register at a predetermined rate, and means for variably actuating said wage register at any one of a plurality of predetermined rates.

22. In an accounting system, a time register, a wage register, and a common actuating mechanism associated with said registers, said actuating mechanism adapted to advance said time register at a rate corresponding to the lapse of time and said wage register at a rate corresponding to any one of a plurality of predetermined rates of wages.

23. An indicating mechanism comprising,

in combination, a plurality of electromagnets adapted to be successively energized during a given period, any one of said electromagnets being energized before the de-energization of the preceding magnet during that period, an actuating mechanism adapted to be operated when the first electromagnet is energized during that period and held in its operated position until the de-energization of the last electromagnet, whereupon said mechanism returns to normal position, and an indicator actuated by said mechanism when the latter is moved one way or the other.

15 24. The combination with an electromagnetic actuating mechanism, of an indicator associated therewith for automatically indicating the number of times that said mechanism has been started or stopped independently of the amount of operation of the mechanism.

25 25. In combination, a plurality of electromagnets, a common armature associated therewith and adapted to be retained in a suitable position as long as any of said electromagnets is energized, said armature assuming its normal position only when all of said electromagnets are de-energized, and an indicating device controlled by said armature.

30 26. The combination with an electromagnetic actuating mechanism having two separate armatures, of a register operatively connected with each armature such registers operated at different rates by the armatures.

35 27. The combination of two registers, and a connecting mechanism between them, one element of said mechanism consisting of a

single electromagnetic device for actuating the registers independent amounts.

28. The combination of two registers, and a connecting mechanism between them, one element of said mechanism consisting of a single electromagnetic device for actuating the registers at different predetermined rates.

29. The combination of two registers, and a connecting mechanism between them, one element of said mechanism consisting of a single actuating device for operating one register proportionally to time and for operating the other register proportionally to wages earned.

30. The combination of two registers, and a connecting mechanism between them, one element of said mechanism consisting of a single actuating device for operating one register proportionally to time and for operating the other register proportionally to wages earned at any desired rate without change in the actuating device.

31. The combination of two registers, and a single actuating mechanism for operating one register proportionally to the number of times the actuating device is operated and for actuating the other register proportionally to the amount of operation of the actuating device.

In witness whereof, I hereunto subscribe my name this 22nd day of March, A. D. 1909.

FREDERICK O. HEUSER.
